DESIGN FOR A LIGHT DELIVERY TRUCK BODY

William Howard Edwards, South Bend, Ind., assignor to Edwards Iron Works, Incorporated, South Bend, Ind., a corporation of Indiana

Application July 20, 1939, Serial No. 86,115

Term of patent 7 years

To all whom it may concern:

Be it known that I, William Howard Edwards, a citizen of the United States, residing at South Bend, in the county of St. Joseph and State of Indiana, have invented a certain new, original, and ornamental Design for a Light Delivery Truck Body, of which the following is a specification, reference being had to the accompanying drawing, forming a part thereof.

In the drawing:

Figure 1 is a rear quarter perspective view of

a light delivery truck body showing my new design; and

Figure 2 is an enlarged rear end elevational view of the truck body shown in Figure 1.

The dominant features of my truck body design reside in the portions shown in the solid black lines in the drawing.

I claim:

The ornamental design for a light delivery truck body, as shown and described.

WILLIAM HOWARD EDWARDS.
